UNITED STATES PATENT OFFICE.

CATHARINE A. GRISWOLD, OF NEW YORK, N. Y.

DESIGN FOR THE ORNAMENTATION OF CORSETS.

SPECIFICATION forming part of Design No. 17,179, dated March 15, 1887.

Application filed February 18, 1887. Serial No. 228,110. Term of patent 14 years.

To all whom it may concern:

Be it known that I, CATHARINE A. GRISWOLD, a citizen of the United States, residing at New York, county and State of New York, 5 have invented and produced a new and original Design for the Ornamentation of Corsets, of which the following is a specification, reference being had to the accompanying drawings, forming part thereof.

10 Figure 1 is a side elevation of a corset containing my new design, and Fig. 2 is a front elevation of the same, these two views being deemed necessary to fully illustrate my design.

15 The leading features of my design consist in a band or stripe on the face of the corset, extending in a curve upwardly from the lower edge on the front toward the waist-line and over the hip portion on each side of the corset, and returning downwardly to the rear lower edge, together with a band or stripe extending on the face of the corset from the top front edge downwardly with a curve, one 20 around and under each of the breast-swells, and returning upwardly to said top edge of the corset.

25 A is the corset, which may be in the usual and ordinary general form.

B B are bands or stripes on the face of the corset, extending in a curve upwardly from the lower edge of the corset on the front upwardly, one over each hip portion toward the waist-line, and returning downwardly to the lower edge on the rear.

C C are bands or stripes on the face of the corset, extending in a curve downwardly from the top front edge of the corset, one around and under each breast-swell D D, and returning upwardly to said top edge.

I claim—

30 The design for the ornamentation of a corset herein shown and described, the same consisting of the bands or stripes B B, extending in a curve upwardly from the lower front edge of the corset, one over the hip portion on each side and returning to said lower edge on the rear, together with the bands or stripes C C, 35 extending downwardly in a curve from the top front edge, one around and under each breast-swell D D, and returning to said top edge, as set forth.
